Primary Examiner — Ricky Pham(74) *Attorney, Agent, or Firm* — Volpe Koenig(57) **CLAIM**

The ornamental design for an oven, as shown and described.

DESCRIPTION

FIG. 1 is a front perspective view of the oven according to my new design;

FIG. 2 is a bottom-front perspective view thereof;

FIG. 3 is a front view thereof;

FIG. 4 is a right-side view thereof, the left-side view being a mirror image thereof;

FIG. 5 is a rear view thereof;

FIG. 6 is a top view thereof; and

FIG. 7 is a bottom view thereof;

FIG. 8 is a front perspective view of a second embodiment of the oven according to my new design;

FIG. 9 is a bottom-front perspective view thereof;

FIG. 10 is a front view thereof;

FIG. 11 is a right-side view thereof, the left-side view being a mirror image thereof;

FIG. 12 is a rear view thereof;

FIG. 13 is a top view thereof; and,

FIG. 14 is a bottom view thereof.

The broken lines in the drawings are intended to show environmental structure that form no part of the design to be patented.
